TRANSVERSE RADIO TUNING INDICATOR FACE PLATE

Maurice D. Katz, 35 Broadway, Lawrence, N.Y. 11559

Filed Mar. 12, 1971, Ser. No. 123,928

Term of patent 14 years

Int. Cl. D14—03, 99

U.S. Cl. D26—1

FIG. 1 is a front perspective view of a transverse radio tuning indicator face plate, showing my new design;

FIG. 2 is a front perspective of a modified embodiment of the face plate disclosed in FIG. 1;

FIG. 3 is a further modified embodiment of the face plate disclosed in FIG. 1; and

FIG. 4 is a front perspective view of the face plate disclosed in FIG. 2 mounted in a radio.

The broken lines representing the radio is shown for illustrative purposes only.

What I claim is:

The ornamental design for a transverse radio tuning indicator face plate substantially as shown and described.
